UNITED STATES PATENT OFFICE.

JAMES R. TIMMINS, OF OKMULGEE, OKLAHOMA, ASSIGNEE OF ONE-FOURTH TO
ORLANDO SWAIN, OF OKMULGEE, OKLAHOMA.

APPARATUS FOR REFINING OIL.

1,105,383.

Specification of Letters Patent. Patented July 28, 1914.

Application filed April 10, 1913. Serial No. 730,807.

To all whom it may concern:

Be it known that I, JAMES R. TIMMINS, a citizen of the United States, residing at Okmulgee, in the county of Okmulgee and State of Oklahoma, have invented certain new and useful Improvements in Apparatus for Refining Oil; and I do declare the following to be a full, clear, and exact description of the invention, such as will enable others skilled in the art to which it appertains to make and use the same.

This invention relates to stills for refining mineral oils, and more especially to those in which the crude oil is vaporized and the vapor condensed; and the object of the same is to produce improvements in apparatus of this character whereby the action of the same will be quickened and cheapened. This and other objects are carried out in the manner hereinafter more fully described and claimed, and as shown in the drawings wherein is illustrated a general perspective view of the entire plant.

Within the still 2 the oil is heated to such an extent that it rises into the dome in the shape of vapor, whence it is conducted upward through a pipe 3 and a valve 4 into the lower cross head 5 of a primary condenser, here shown as a manifold 6 which is made up of a number of fine pipes connecting said cross head with an upper cross head 7, and all of these pipes are exposed to the air so that the vaporized oil therein may be cooled if not condensed. Such portions thereof as are condensed drop back into the still and go through the process again, but the lighter vapors which reach the upper cross head 7 pass through an upwardly inclined outlet pipe 12, thence over an arch 13 and downward through a pipe 14 into a secondary condenser, which, like the first, may consist of a lower cross head 15, a number of fine pipes 16, and an upper cross head 17 as shown. This condenser need not be as large as that first above described, because obviously a large percentage of the vapors from heavier oil will have been condensed within the first one, and it will be only the lighter vapors from the lighter oil which will pass over the pipe 12 and arch 13 into the second condenser. The condensates from the latter pass out the pipe 19, through valve 18, and then through pipe 9 into a coil 11 which is disposed in a cooling tank 10 containing water or other cooling agent as shown dia-

grammatically in the drawings. By this means the condensate, stripped of the vaporized portions of the oil as initially treated, is conveyed eventually through the pipes 34 to the tank 35; but if it is found that it would be wise to treat the same again, it may be passed through the pipe 9 and valve 8 back to the still 2 in which it can be subjected to re-treatment in the manner above described.

The very lightest vapors which are not condensed within the second manifold pass from its upper cross head 17 through an outlet pipe 22 into the top of a separator, here shown as a cylinder 26, where the oil passes out through the outlet 29 and valve 28, and into the coil 11 of the main outlet 9 as above described. The lightest of the oil vapors in the cylinder 26 pass out the vapor outlet 27 near its upper end and lead to a coil 31 within a cooling box 30 as shown. Within this coil they are subjected to the cooling influences of the proper agent within the box 30; whatever vapors may come over through both condensers and the separator 26 are condensed; and finally they are led through the pipe 32 into a tank 33. So also the heavier oils which are drawn from all the outlets are cooled within the coil 11 and led through the pipe 34 to the tank 35. It is also quite within the scope of my invention that the intermediate grades of oils could be collected in separate tanks by conducting the outlet pipes 9, 19, and 29 through separate coils instead of through the single coil 11 as shown; but this detail needs no further elaboration. During the process of distillation or refining as carried out by this apparatus, the vaporized oil after leaving the still is driven into the larger manifold 6 several times before the process is complete. By this I mean the oil in the still may be so heated that the vapor rises therefrom in waves or pulsations, that portion of each which is condensed falling back into the still to be again vaporized and that portion not condensed passing on throughout the course indicated. On entering the manifold 6 and finding it cold, much of the vapor at the first impulse will be condensed and will fall back into the still to be vaporized a second time; on the second impulse a smaller proportion will be condensed and fall back for renewed action; finally the temperature of the rather dia-

the pipe 6 will be raised as the atmosphere will permit, and a substantial proportion of the vapors will pass through the outlet 12 and arch 13 into the manifold 16. Having once passed the arch it is impossible for it to return, no matter what form it is in, and it must then eventually reach one of the coils and one of the tanks. In the drawings I have not considered it necessary to show the means for supporting the condensers or the separator, nor the means for admitting water or other cooling agent to the tanks 10 and 30. In fact, the drawings are to an extent diagrammatic, and the proportions of parts need not be elaborated herein.

What is claimed as new is:

1. The herein described apparatus for refining oil consisting of a still, a pipe rising therefrom and having a valve, a primary condenser with whose lower end said pipe is connected, a secondary condenser, a pipe connecting the upper end of the first condenser with the lower end of the second condenser, a vapor pipe leading from the upper end of the second condenser to a cooling coil, an oil pipe leading from the lower end of the second condenser to a separate cooling coil, and a branch pipe leading from said oil pipe back to the still and containing a valve.
2. The herein described apparatus for refining oil consisting of a still, a pipe rising therefrom and having a valve, a primary condenser with whose lower end said pipe is connected, a secondary condenser, a pipe connecting the upper end of the first condenser with the lower end of the second condenser, a vapor pipe leading from the upper

end of the second condenser, a separator into whose upper end said vapor pipe leads, a vapor outlet pipe leading from the upper portion of the separator to a cooling coil, an oil pipe leading from the lower end of the second condenser to a cooling coil, a second oil pipe leading from the lower end of said separator into the first-mentioned oil pipe and then to said cooling coil, and a branch pipe leading from said oil pipe back to the still and containing a valve.

3. The herein described apparatus for refining oil consisting of a still, a dome thereon, a valved pipe rising from the dome, a manifold with whose lower end said pipe communicates, a second manifold located at a higher level than the first, a pipe connecting the upper cross head of the first manifold with the lower cross head of the second, an arch within the length of this pipe for the purpose set forth, a vapor outlet leading from the upper cross head of the second manifold, means for treating the vapor passing therethrough, an oil outlet leading from the lower cross head of said second manifold, means for treating the oil flowing therethrough, and a branch outlet leading from the main outlet back to said dome and provided with a valve, for the purpose set forth.

In testimony whereof I have hereunto set my hand in presence of two subscribing witnesses.

JAMES R. TIMMINS.
